UNITED STATES PATENT OFFICE

FRED C. TRUESBURY, OF ROCKFORD, ILLINOIS, ASSIGNOR TO J. L. CLARK MANUFACTURING CO., OF ROCKFORD, ILLINOIS, A CORPORATION OF ILLINOIS

CONTAINER

Application filed June 20, 1931. Serial No. 545,682.

The invention relates generally to containers and more particularly to containers having valved openings in the walls thereof through which the contents may be removed or discharged.

An important object of the present invention is to provide a container for condiments and similar finely comminuted substances, said container embodying a simple and inexpensive valve structure through the medium of which the container may be filled and its contents removed either by pouring or sifting, or by the withdrawal of different measured quantities of material from the container by the use of a spoon pressed against differently shaped edges of the outlet opening.

Another object is to provide a valve structure of this character adapted for use on small containers.

Another object is to provide a container having a valve structure for controlling the removal of the contents thereof and embodying new and improved means to prevent undesired loss of material, particularly during shipping of the container.

Another object is to provide a container having valve structure embodying a rotatable valve member and employing improved and simplified means to maintain the valve member in position to seal the container.

In the drawing, which illustrates three embodiments of the invention:

Figure 1 is a fragmental vertical sectional view of a container embodying the invention in its preferred form, the section being taken substantially along the line 1-1 of Fig. 3 and showing the valve member before it has been secured in place.

Fig. 2 is a fragmentary view taken along the line 2-2 of Fig. 3 showing the valve member after it has been secured to the container.

Fig. 3 is a plan view showing the container with all of the outlet openings closed.

Fig. 4 is a plan view showing the sifter holes opened for use.

Fig. 5 is a plan view showing the valve member positioned to provide a relatively small pouring opening.

Fig. 6 is a plan view showing the valve

member positioned so as to close the sifter holes and provide a comparatively large opening for measuring purposes.

Fig. 7 is a plan view showing an alternative form.

Figs. 8 and 9 are sectional and plan views respectively showing another alternative construction.

In the form shown in Figs. 1 to 6, the invention is embodied in a container of substantially square cross section having a side wall 11 and closed at its upper end by an end wall 12. The end wall 12 is provided with a movable valve or closure plate 13 for governing a comparatively large opening 14 and sifter holes 15 formed in the wall 12 beneath the plate.

The closure plate 13 is preferably mounted for rotative movement in close sliding contact with the outer surface of the end wall 12 and to this end has a curved peripheral edge, with a central aperture 16 (Fig. 3) therein through which pivot means such as prongs 17 may extend. The prongs 17 are struck outwardly from the metal of the wall 12 and are oppositely bent into contact with the outer surface of the plate 13 as shown in Figs. 2 to 6. The plate 13 and the wall 12 beneath the plate are preferably bent outwardly to provide a slightly dome-like form, the dome-like portion of the wall 12 being formed with a central circular depression or recess 12^a within which the closure plate 13 rotates.

To insure close contact of the plate and the wall 12 and thereby securely seal the openings 14 and 15, the plate 13 is initially formed with a greater radius of curvature than the wall 12 so that the central portion of the plate is initially spaced from the wall 12, as shown in Fig. 1. By pressing the center of the plate 13 against the wall 12 and bending the prongs 17 as shown in Fig. 2, the resiliency of the plate is caused to press the edges of the plate firmly against the bottom of the recess 12^a, and the deformation of the plate 13 serves to press its edges firmly into engagement with the vertical side walls of the recess 12^a so as to provide a more effective seal for the container. An upwardly extend-

ing boss or lug 19 on the plate 13 provides for manual engagement and operation of the plate.

As above pointed out, the wall 12 has sifter openings 15 as well as a comparatively large opening 14 formed therein, and these openings are arranged so that both may be simultaneously closed by the plate 13, or may be selectively opened in varying amounts by rotation of the plate. To this end the plate 13 has a segment cut away at one side thereof to provide a straight edge 20 offset slightly to one side of the pivotal axis of the plate so that the plate is adapted in its pivotal movement to gradually uncover either the opening 14 or the sifter holes 15.

The present embodiment of the invention contemplates utilization of the opening 14 to facilitate withdrawal of different measured quantities of material from the container through the use of a spoon, and to this end the opening 14 has one of its edges 14^a formed straight while the other edge is arcuate in form as indicated at 14^b. Thus as shown in Fig. 6 of the drawings, the opening 14 is of sufficient size to permit passage of the bowl 21 of a spoon so that the bowl may be withdrawn from the container with its side edges in contact with either of the edges 14^a or 14^b to strike off the contents of the spoon. By selective use of the edges 14^a or 14^b a level or heaping spoonful of material may be withdrawn from the container.

To maintain the area of the closure plate 13 at the minimum and thus adapt the structure for use on small containers, the straight edge 14^a of the opening 14 in the top wall 12 is slightly offset from the rotative axis of the plate 13 while the arcuate edge 14^b is located outwardly of the edge 14^a and adjacent to the curved outer edge of the recess 12^a. Also, the straight edge 20 of the closure plate is positioned similarly to the edge 14^a of the closure plate with the result that by locating the sifter holes 15 closely adjacent to one end of the opening 14, the imperforate plate 13 is adapted to close simultaneously both the opening 14 and the sifter holes 15, as shown in Fig. 3. On the other hand the sifter openings 15 will be closed when the opening 14 is uncovered as shown in Fig. 6; and the opening 14 may be closed when the sifter holes alone are uncovered (Fig. 4). Fig. 5 shows the opening 14 partially uncovered near one edge of the plate, for pouring purposes.

In Fig. 7 a modified form is shown wherein in sifter holes 15^a are formed in the closure plate 13 rather than in the wall 12 as in the form shown in Figs. 1 to 6.

To insure complete closure of the container when desired, as during shipping, a detent means is provided to act between the closure plate 13 and the wall 12. To this end a pair of bosses 22 struck upwardly from the

bottom of the recess 12^a (Figs. 2 and 3), are arranged to abut the straight edge 20 of the plate 13 at spaced points to hold it in its closed position. Free movement of the closure plate is obtained by positioning the bosses adjacent to the outer edge of the recess 12^a and providing a downwardly facing groove 23 about the edge of the plate 13 into which the bosses 22 may extend. This groove 23 may be formed by beading the edge of the plate as shown in Figs. 1, 2 and 3, and preferably this bead extends also along the straight edge 20 with the result that the plate is materially strengthened. After the closure plate 13 has been moved from its closed position, one of the bosses 22 projects upwardly into the groove 23 as shown in Fig. 4 and free movement of the plate results. In some positions, both bosses 22 extend into the groove, and whenever the plate is restored to its closed position the bosses act to hold the plate against undesired displacement. It will be noted that the bead along the straight edge 20 extends transversely of the groove 23 to provide an abutment for engagement by the bosses 22.

Through efficient utilization of the area of the closure plate and wall 12 as above described, it is possible to make the opening 14 quite large with respect to the size of the container, and as a result it is also possible to use the opening 14 for filling purposes. This enables the manufacture of the container to permanently fasten both of the ends on the container and thereby simplifies the use of the container and avoids the necessity for using frictionally held telescoping parts. Thus after the container has been filled, the only operation necessary is the rotation of the closure plate 13 from the position shown in Fig. 6 to the position shown in Fig. 3. Moreover the arrangement and shape of the openings 14 and 15 maintains the size of the valve structure at the minimum and yet permits its use for pouring, sifting or measuring of the contents of the container. In addition, it will be seen that the flanged edge of the cover plate 13, being forced against the vertical side walls of the recess 12^a in the attachment of the plate, serves to provide an additional seal cooperating with the close sliding joint with the bottom of the recess to prevent undesired loss of material from the container.

Figs. 8 and 9 illustrate another alternative construction adapted to guard against loss of material from the container during shipment. This construction is particularly adapted for use on containers embodying a slip cover 24 which may be placed on the wall 11 of the container after the container has been filled. The slip cover 24 comprises inner and outer cup shaped members 25 and 26 grooved together in their sides as at 27 to permit relative rotation, and having

measuring and sifter openings 28 and 29 therein adapted to be opened or closed selectively by relative rotation of the two members 25 and 26. Between the two members 5 25 and 26 an imperforate sheet 30 of frangible material such as paper is positioned to close the openings 28 and 29. Preferably the sheet 30 is secured as by adhesive to the outer member 26 for rotation therewith so that to open the container it is only necessary to perforate the sheet at one point, as for example, by cutting an opening therein to correspond with the opening 28 in the outer plate. The opening in the sheet 30 is made 10 when the openings 28 of the two members are in registry, after which the sifter holes 29 may be uncovered simply by rotation of the member 26.

I claim as my invention:

20 1. A container having side walls and an end wall, said end wall having an opening formed therein, a closure member mounted on said wall for rotation about an axis positioned at one side of said opening and shaped to close said opening or in rotation about said axis to gradually uncover said opening, said opening being formed to provide a mouth having a thin straight edge and a thin curved edge, said mouth being of a size adapted to permit the bowl of a spoon to be withdrawn therefrom with its edges in contact with either of the side edges of the mouth to measure different quantities of material on the spoon, and said wall having a plurality of sifter 25 holes formed therein adjacent to one end of said opening and positioned to permit closure thereof by said closure member while said opening is closed.

40 2. A container having a wall member with an opening therein, a closure member rotatably mounted in close sliding contact to said wall member for covering or uncovering said opening, said members having interengageable abutments thereon for restraining the closure against movement, one of said members having a groove formed therein centered on the axis of rotation of said closure and into which the abutment of the other member may extend to permit free rotation 45 of said closure member.

50 3. A container having an opening in one wall, a closure member rotatably mounted on said wall in close sliding contact therewith and adapted to cover or uncover said opening, said closure member having a bead formed about its edge centered on the axis of rotation of the member to reinforce the member and provide a groove facing toward said wall, an abutment on said closure member extending transversely of said groove, and an abutment on said wall for engagement with the abutment on said closure member to restrain movement thereof and positioned to extend into said groove when the closure 55 member is rotated.

4. A container of the character described having an end wall with an opening therein, a closure plate adapted selectively to close or uncover said opening, said plate being initially formed so that the central portion thereof is spaced from said end wall while the edges thereof contact said wall, and means engaging said wall and said plate providing a pivot for said plate and clamping said central portion of the plate against said wall whereby the resiliency of said plate presses the edges thereof into firm contact with said wall.

5. A container of the character set forth having an end wall with a circular recess formed therein and an opening eccentrically located in the bottom of said recess, a closure member in the form of a thin disk of resilient metal, located in said recess and initially formed so that the central portion of the member is spaced from the bottom of said recess, and pivot means for said member engaging said wall and said member to draw the central portion of said member against the bottom of said recess and force the edges of the member into contact with the sides of said recess.

6. A container having an end wall member and a closure member movably mounted thereon, said wall and said member having openings therein adapted in one relation to be closed and in another to be in registry, and an imperforate sheet of frangible material positioned between said members and secured to the closure member to close said openings.

7. A container having an end wall member with an opening therein and a closure member movably mounted on said end wall for closing said opening, one of said members having sifter holes formed therein adapted to be opened in one relation of the parts, and an imperforate sheet of frangible material positioned between said members to close said opening and said sifter holes and secured against movement relatively to the other one of said members.

In testimony whereof, I have hereunto affixed my signature.

FRED C. TRUESBURY.
